DESIGN FOR A COMBINED COVER AND UTENSIL SUPPORTING STRUCTURE FOR COOK STOVE TOP BURNERS

Claude E. Parker, Chicago, Ill., assignor to Gas
Products Corporation, Chicago, Ill., a corpora-
tion of Illinois

Application August 3, 1940, Serial No. 94,297

Term of patent 7 years

To all whom it may concern:

Be it known that I, Claude E. Parker, a citizen
of the United States, residing at Chicago, in the
county of Cook and State of Illinois, have in-
vented a new, original, and ornamental Design
for a Combined Cover and Utensil Supporting
Structure for Cook Stove Top Burners, of which
the following is a specification, reference being
had to the accompanying drawing, forming part
thereof.

Figure 1 is a plan view of a combined cover and
utensil supporting structure for cook stove top
burners embodying my new design.

Fig. 2 is a perspective view of the structure.

I claim:

The ornamental design for a combined cover
and utensil supporting structure for cook stove
top burners, substantially as shown.

CLAUDE E. PARKER.
